UNITED STATES PATENT OFFICE.

FREDERIC AUMONIER, OF LONDON, ENGLAND.

DESIGN FOR WALL-PAPER.

SPECIFICATION forming part of Design No. 23,005, dated January 9, 1894.

Application filed December 13, 1893. Serial No. 493,611. Term of patent 3½ years. Registered in England March 3, 1893, No. 208,514.

To all whom it may concern:

Be it known that I, FREDERIC AUMONIER, (trading as WM. WOOLMANS & CO.,) a subject of the Queen of Great Britain, and a resident of 110 High Street, near Manchester Square, London, England, have invented a new and useful Design for Wall-Paper, (registered in Great Britain on the 3d day of March, 1893, No. 208,514,) of which the following is a specification.

This design for wall paper having frieze filling and dado, is represented in the accompanying drawing.

The frieze consists of festoons of leaves and flowers and festoons of leaves and berries suspended from winged ornamental scrolls hung from the upper beading. The center of the festoons of leaves and flowers has a medallion surmounted by spread out leaves forming a support a kind of tablet, above which are two reversed dolphins, and having at each end a cornucopia the spaces between the festoons being filled with a scroll, from which a flambeau springs.

Above the festoon of leaves and berries is arranged a crouching lion, and below is a table urn having an ornamental scrolled device emanating from both sides of which the aforesaid flambeau forms a part.

The bottom beading of the frieze has flowers with checkered markings between.

The filling is composed of vases on pedestals having scroll brackets, beneath which are lily like flowers having stems meeting the center of a festoon; above the vases are other festoons suspended from a portico with an entablature of a Grecian lamp, from which is suspended a horoscope inclosed in a festoon of flowers, with oak leaves filling in the space between it and a couple of winged sphinxes forming supports to the portico. Above the portico are sea horses, the tails of which approach and support a scroll from which a lamp appears with a shade above, this having gas like branches over. The intervening spaces

between two sets of the foregoing are composed of candlesticks, the flame from which has a curled appearance and is surmounted by a peacock, above which is a medallion hanging from an arch of flower leaves and 50 kept in place by festoons connected to curled brackets, which project from the sides of the porticos of the intermediate pattern. Above the arch is another bracket having pedestals of candlestick like formation inclosing a cactus head. 55

The spaces between the various objects cited have leaves and flowers terminating from scrolls of various forms.

The dado consists of panels, one panel having an oblong base ornamented above which are two sitting griffins, each having one leg raised, forming a kind of support to a rectangular entablature, on each of which is a table urn with flambeau. The tablet supports a 65 kind of table, on which are two dolphins, and an urn, from which leaves and stems appear, this being surmounted by an Egyptian border provided at intervals with tablets variously ornamented. The panels of the dado 70 are separated by projecting fascias, within a portion of which, dancing lions standing on a center piece and leaning against two upright rods also which form supports to an upper portion of the fascia in which are scrolls, festoons, and lilies merging from a vase. 75

The spaces between the several parts of the paneling are filled in with hanging rods terminating with stars.

I claim—

The design for wall paper, substantially as herein shown and described.

The 10th day of March, 1893.

FREDERIC AUMONIER.
